CONVEYER BELT

Chester M. MacChesney, Chicago, and Allen B. Wilson, Evanston, Ill., assignors to Acme Steel Company, Chicago, Ill., a corporation of Illinois

Application December 24, 1937, Serial No. 181,476

6 Claims. (Cl. 198—189)

This invention relates to improvements in conveyer belts and its purpose is to provide an improved form of conveyer belt made up of metal plates which are pivotally connected together to form a substantially continuous bearing surface for conveying loose materials and the like. The present invention is an improvement upon the conveyer belt described and claimed in the co-pending application of Chester M. MacChesney, Serial No. 87,141, filed June 25, 1936, wherein there is disclosed a form of conveyer belt made up of a plurality of metal plates arranged in rows transversely of the belt with the plates of each row staggered with respect to those of the next adjacent rows and with tongues formed on the plates intermeshing with similar tongues on the plates in adjacent rows, and with pivot pins engaging bearing sleeves carried by the projecting tongues for establishing pivotal connections between the plates of adjacent rows.

The principal object of the present invention is to provide an improvement on the conveyer belt described above by providing means at the ends of the rows of plates for preventing the withdrawal of the pins which establish the pivotal connections between the plates in adjacent rows. A further object of the invention is to provide a conveyer belt of the kind referred to comprising auxiliary protector plates which are detachably secured to certain of the pivotally connected plates at the ends of the rows for the purpose of protecting the edges of these plates against contact with parallel guide members which are commonly employed at the sides of the path of travel of a conveyer belt. A further object is to provide a conveyer belt of the kind described having plates detachably mounted at the ends of the rows of pivotally connected plates for preventing the withdrawal of the pivot pins and at the same time protecting the edges of the belt from damage by contact with guide members adjacent to the path of travel of the belt. Other objects relate to various features of construction and arrangement which will appear more fully hereinafter.

The nature of the invention will be understood from the following specification taken with the accompanying drawings in which one embodiment is illustrated.

In the drawings,

Figure 1 shows a side elevation of a conveyer belt embodying the improvements of the present invention;

Fig. 2 shows a partial top plan view, on an enlarged scale, of the conveyer belt illustrated in Fig. 1;

Fig. 3 shows a side elevation of the portion of the conveyer belt shown in Fig. 2;

Fig. 4 shows a longitudinal section taken on the line 4—4 of Fig. 2;

Fig. 5 shows a transverse section taken on the line 5—5 of Fig. 2;

Fig. 6 shows a transverse section taken on the line 6—6 of Fig. 2;

Fig. 7 is a perspective view of one of the metal plates embodied in the conveyer belt shown in Figs. 1 to 6, inclusive;

Fig. 8 is a perspective view of one of the plates employed at the ends of the rows for connection with one of the protector plates of the present invention;

Fig. 9 is a perspective view of one of the filler plates which are employed at the ends of certain of the rows in order to cause the ends of the rows to align with each other at the sides of the belt;

Fig. 10 is a perspective view of one of the protector plates which, according to the present invention, are mounted at the sides of the belt to prevent the removal of the pivot pins and to protect the edges of the other plates.

In the accompanying drawings, the invention is shown as being embodied in an endless conveyer belt 10 which is mounted to travel around supporting pulleys or rolls 11 which are secured on shafts 12. One of these shafts is driven to cause the upper stretch of the belt to move in the direction of the arrow 13 and this load conveying portion of the belt is supported at intervals by idler rolls 14 carried by shafts which are journaled in suitable bearings. The belt 10 is made up of a plurality of plates 15, formed of sheet steel or the like, which have the form shown particularly in Fig. 7. Each plate 15 is provided on opposite sides with notches 15^a of rectangular form which are similar in size, and the formation of these notches provides projecting tongues 15^b at opposite sides of each notch. Each projecting tongue 15^b has its ends downwardly curled to form a sleeve or bearing member 15^c adapted to be engaged by one of the pivot pins by which the metal plates are connected together. Midway between the ends 15^d of each plate, the metal of the plates has a depression 15^e therein which is formed by a downwardly extending V-shaped rib 15^f. These ribs extend between the opposite notches 15^a and are of substantially the same depth as the bearing sleeve 15^c so that when a plurality of the plates are connected together the ribs 15^f are adapted to engage the supporting rolls 14 between the bearing sleeves 15^c, thereby preventing up and down motion or vibration of the load conveying portion of the belt during its travel.

Since the plates 15 in each row are staggered with respect to those in adjacent rows, it follows that portions of these plates in alternate rows will project beyond the ends of the corresponding plates in intermediate rows and in order that these intervening spaces may be occupied, a plurality of

filler plates 16 are provided, having the form shown particularly in Fig. 9. Each plate 16 is constructed as a half portion of one of the plates 15 being provided on opposite sides with angular notches 16^a and adjacent these notches with projecting tongues 16^b having sleeve-like bearing portions 16^c formed thereon. At one end of the plate 16, there is a down-turned flange 16^d which corresponds in size and form to a half portion of one of the ribs 15^f formed on a plate 15. When the plates are assembled as shown in Figs. 2, 3 and 4, each notch 15^a is adapted to receive two of the tongues 16^b carried by two plates 15 in an adjacent row, or a notch 15^a may be occupied by one of the projections or tongues 16^b and one of the tongues 16^b at the edges of the belt. The notches 15^a are fully occupied by the tongues 15^b and 16^b, except for small slots at the inner margins of the notches as shown in Fig. 2, and a substantially continuous metallic bearing surface is therefore provided for the materials being conveyed. The plates which are arranged in intermeshing fashion as shown in Fig. 2 are pivotally connected by pivot pins 17 of cylindrical form which extend through the aligning bearing sleeves of plates in adjacent rows.

The features described above constitute the invention of the said Chester M. MacChesney and the present improvement relates to the provision of a belt of that type comprising a plurality of protector plates 18 which have the form shown particularly in Fig. 10. Each plate 18 comprises a body portion 18^a adapted to rest upon the top of the edge portion of one of the plates 15, and a down-turned flange 18^b which is adapted to extend downwardly alongside the edge 15^d of a plate 15. The body portion 18^a of each plate 18 is provided with a pair of tongues 18^c which are adapted to pass through an elongated slot 15^e formed in one of the plates 15 at the end of one of the rows of plates. The depending flange 18^b of each plate 18 is provided with a pair of downwardly and inwardly inclined punched projections 18^d which are adapted to hook beneath the edge 15^d of one of the plates 15 as shown particularly in Fig. 6. After putting one of the plates 18 in place with the projections 18^d extending beneath the edge 15^d of a plate 15 and with the tongues 18^c entering one of the slots 15^e, the tongues 18^c are then reversely bent as shown at 18^e in Fig. 6, thereby securely holding the plate 18 in position. By a reverse operation the plates 18 may be removed. These plates 18 are mounted at each end of alternate rows of plates 15 and occupy positions on opposite sides of one of the intervening filler plates 16, as shown in Fig. 2, with their flanges 18^b closing the ends of the bearing sleeves 15^f at the sides of the belt to prevent the removal of the pivot pins 17. The flanges 18^b of these protector plates extend outwardly beyond the flanges 16^d which are formed on the plates 16 and thus serve to protect these flanges as well as the edges 15^d of the plates 15 from contact with the parallel guide members 20 which are customarily employed along the sides of the path of travel of the conveyer belt. The plate 18 presents smooth surfaces of considerable area for contact with the guide members 20 so that the catching of any parts of the belt on the guide members is prevented and damage to the plates 15 and 16 is avoided.

Although one form of the invention has been shown and described by way of illustration, it will

be understood that it may be constructed in various other embodiments coming within the scope of the appended claims.

We claim:

1. A conveyer belt comprising a plurality of plates, pivot pins for connecting said plates, and protector plates carried by certain of said first named plates for preventing the withdrawal of said pins, said protector plates and the plates by which they are carried having coacting interlocking parts permitting said protector plates to be readily detached. 5

2. A conveyer belt comprising a plurality of plates, pivot pins for connecting said plates to form an endless flexible belt, said plates extending edge to edge in the longitudinal stretches of the belt to form a substantially flat continuous surface, and protector plates attached to the outer surfaces of certain of said first named plates and having flanges extending downwardly past the 10 edges of said first named plates at the sides of the belt to prevent the withdrawal of said pins. 15

3. A conveyer belt comprising a plurality of plates having parts intermeshing with each other to prevent relative separation of said plates 20 transversely of the belt, pivot pins engaging parts of said plates for pivotally connecting adjacent plates, and means carried by said belt and having flanges extending downwardly at the sides of said belt for preventing endwise movement of said 25 pivot pins with respect to said plates.

4. A conveyer belt comprising a plurality of metal plates arranged in rows and having bearing portions at their edges, pivot pins engaging said bearing portions to connect the plates of adjacent 30 rows, certain of said plates at the ends of said rows being provided with slots, and protector plates seated on said last named plates and having flanges extending downwardly to prevent the withdrawal of said pivot pins, said protector 35 plates having tongues engaging said slots to hold said protector plates in position.

5. A conveyer belt comprising a plurality of metal plates arranged in rows and having bearing portions at their edges, pivot pins engaging said 40 bearing portions to connect the plates of adjacent rows, certain of said plates at the ends of said rows being provided with slots, and protector plates seated on said last named plates and having flanges extending downwardly to prevent the 45 withdrawal of said pivot pins, said protector plates having tongues engaging said slots to hold said protector plates in position, said downwardly extending flanges of said protector plates having 50 inwardly inclined projections adapted to underlie 55 said first named plates on which said protector plates are mounted.

6. A conveyer belt comprising a plurality of flat plates arranged in rows transversely of the belt and having longitudinally projecting parts intermeshing with each other to prevent relative lateral separation of the plates, pivot pins engaging the intermeshing parts of said plates for pivotally connecting adjacent rows of plates, thereby forming a belt having a substantially continuous flat outer surface, and protector plates resting on and secured to certain of said first named plates at the ends of said rows and having parts projecting past the ends of said pivot pins for preventing endwise movement of all of said pins. 60
